(57) **CLAIM**

The ornamental design for a teardrop wall clock, as shown and described.

DESCRIPTION

FIG. 1 is a perspective view of a teardrop wall clock according to the present invention.

FIG. 2 is a front elevational view of the teardrop wall clock of FIG. 1.

FIG. 3 is a top plan view of the teardrop wall clock of FIG. 1.

FIG. 4 is a bottom plan view of the teardrop wall clock of FIG. 1.

FIG. 5 is a right side elevational view of the teardrop wall clock of FIG. 1.

FIG. 6 is a left side elevational view of the teardrop wall clock of FIG. 1; and,

FIG. 7 is a rear elevational view of the teardrop wall clock of FIG. 1.

The broken lines shown in the drawings are for illustrative purposes only and form no part of the claimed design. The views are shown drawn to different scales.
